B. F. UPHAM.
PRINTING PRESS.
APPLICATION FILED SEPT. 16, 1919.

Patented Aug. 3, 1920.

UNITED STATES PATENT OFFICE.

BURT F. UPHAM, OF BOSTON, MASSACHUSETTS, ASSIGNOR TO UNITED PRINTING MACHINERY COMPANY, OF BOSTON, MASSACHUSETTS, A CORPORATION OF MASSACHUSETTS.

PRINTING-PRESS.

1,348,253.

Specification of Letters Patent.

Patented Aug. 3, 1920.

Application filed September 16, 1919. Serial No. 324,072.

To all whom it may concern:

Be it known that I, BURT F. UPHAM, a citizen of the United States, residing at Boston, in the county of Suffolk and State 5 of Massachusetts, have invented certain new and useful Improvements in Printing-Presses; and I hereby declare that the following is a full, clear, and exact description thereof, reference being had to the accompanying drawings, which form part of 10 this specification.

This invention is an improvement in rotary sheet printing presses, and its object is to produce a press wherein the quantity 15 of product obtainable in a given time will be greatly increased as compared with the ordinary type of printing presses of same size; the impressions will be accurately registered; and the sheets be carried to and 20 through the successive printing couples and to the delivery points by traveling sheet gripping devices.

The invention will be fully understood from the following description of the 25 machine illustrated in the accompanying drawings, which will enable others to understand and use the invention; and the essential features of the invention and novel combinations and constructions of parts for which 30 protection is desired are set forth in the claims following the description.

The accompanying drawing represents 35 diagrammatically a longitudinal sectional elevation of one form of printing press embodying the invention.

In said drawing the plate-cylinders 1 and 2 are adapted to carry printing surfaces of any suitable kind, and are supplied with ink from fountains F and F', respectively, in 40 the usual manner.

An impression-cylinder 1^a co-operates with plate cylinder 1, and an impression-cylinder 2^a co-operates with plate-cylinder 2. The impression-cylinders 1^a, 2^a are arranged close 45 together and substantially intermediate the plate-cylinders 1 and 2.

The plate-cylinder 2 has a gap 2^b; and the impression-cylinder 1^a has a gap 1^b, for a purpose hereinafter shown.

50 In the present invention instead of the impression-cylinders being provided with grippers to handle the sheets, the sheets are

carried through the successive printing couples to the point of delivery by means of traveling gripping devices, preferably 55 mounted upon an endless carrier 3, which may be of any suitable construction.

As shown the carrier has endless sprocket chains that run over sprockets on or attached to the ends of the cylinders; and 60 said carrier extends from the top of the plate-cylinder 2 down under and partly around the impression-cylinder 1^a; up and between the impression-cylinders 1^a and 2^a; partly around impression-cylinder 2^a and 65 between it and plate-cylinder 2; thence back to and partly around a cylinder or sprockets 4 mounted at the rear of the press and above the sheet delivery table; and thence 70 forward from the sprockets 4 to the top of cylinder 2, thus making a complete endless circuit.

The sheet gripping devices are attached to the carrier and may be composed, as 75 shown, of transverse bars 3^c, mounted on and between the carrier chains, with which bars coat grippers 3^a mounted on shafts 3^b also mounted on the carrier chains; and which grippers may be normally closed by suitable springs, as usual (not shown); and 80 can be opened and closed at the desired points by means of suitable gripper actuating devices (not shown) such as are commonly employed in printing presses, and all of which will be readily understood by those 85 skilled in the art.

The endless carrier chains may be directed past idler sprockets 4^a located between the plate-cylinder 2 and the impression-cylinder 1^a, as indicated in the drawing. 90

The sheet gripping devices on the carrier are spaced apart a distance slightly greater than the length of the longest sheet that the press is designed to print; and the carrier is driven at such speed that the sheet grippers thereon will travel at a rate of speed synchronizing with the peripheral speed of the plate and impression cylinders. 95

The gripping devices on the carrier are 100 enabled to pass around the plate-cylinder 2 and impression-cylinder 1^a by reason of the gaps 2^b and 1^b, with which the gripping devices successively register as they travel with

and around such cylinders and between the printing couples, as indicated in the drawing.

The sheets to be printed are fed to the grippers 3^a at any convenient point, and presented thereby successively to the plate-cylinders of the printing couples. Preferably the sheets are fed to the grippers 3^a at the point T, adjacent the cylinder 1, by means of suitable feed mechanism adapted to alternately deliver sheets S from a table 6, and sheets S' from a table 6^a, to the grippers on the endless carrier.

As shown a feed cylinder 5 is provided having grippers 5^a adapted to take sheets at the point T' from grippers 5^c of a feed cylinder 5^b that alternately takes sheets from table 6 and from a transfer cylinder 5^a; which transfer cylinder is provided with grippers 5^e to take sheets from table 6^a and transfer them to cylinder 5^b at the point T^e.

The cylinder 5^b thus takes sheets alternately from table 6 and from transfer cylinder 5^a, so that ample time is given for positioning the sheets S, S' on the tables 6, 6^a against their respective sheet stops 6^b and 6^c. Twice as much time is allowed for positioning the sheets on the respective feed tables as would be permitted if all sheets were fed from one table. The sheets may be fed up to the stops 6^b, 6^c in the usual manner either manually or by mechanical means.

I do not herein claim the sheet feeding mechanism, that forming the subject-matter of a divisional application.

Suitable devices for operating the grippers 5^a, 5^c, and 5^e are provided at the points T, T' and T^e; such devices being well understood are not illustrated.

The parts are so timed that sheets S and S' are alternately taken from the tables 6 and 6^a and delivered in alternation to the successive grippers 3^a on the endless carrier at the point T.

Each sheet taken by grippers 3^a is carried from the point T first between the plate-cylinder 1 and impression-cylinder 1^b, (the grippers 3^a occupying the gap 1^b during the passage of the sheet partly around the cylinder 1^a), and the sheet is printed on one side from the printing surfaces on cylinder 1. The grippers 3^a then carry the sheet to and partly around impression-cylinder 2^a and between such cylinder and plate-cylinder 2, (during which passage the grippers 3^a occupy the gap 2^b in the cylinder 2), and the sheet is perfected by the printing surface on plate-cylinder 2.

After being printed on the plate-cylinder 2 the sheet is carried rearward by the traveling grippers 3^a to the point of delivery; I preferably employ an automatically lowering delivery table 8 which may be of any suitable kind, onto which the printed sheets

are piled, and from which they can be lowered onto a truck 8^a in the usual manner.

It will be noticed that the delivery table is outside of, and, in the example shown, below the lower run of the carrier 3. This is very advantageous as it permits the sheet receiving tables to be readily manipulated, and moved into and out of position beneath the carrier without interfering with the operation of the carrier; and this construction provides ample room for the accommodation of the sheet receiving tables, and for the trucks carrying same which could not be practically used if the delivery table had to be located within the orbit of the endless carrier.

The grippers 3^a are caused to release the sheet at the point D above the delivery table, by means of suitable gripper operating devices, which being well known are not shown.

I preferably use an offset web O on impression-cylinder 2^a. The offset web is shown as passing from a roll 7 to and partly around impression-cylinder 2^a and between it and plate-cylinder 1^a, down over a guide 7^b adjacent cylinder 1^a, and back to a roll 7^a. The offset web rolls 7, 7^a may be mounted and operated in the usual manner by the usual means, so that the offset web O will travel in the direction of rotation of the impression-cylinder 2^a, and effectively prevent offset from the printed sheets S, S' upon the cylinder 2^a, while such sheets are receiving a perfecting impression from the surfaces on plate-cylinder 2.

It will be seen that each sheet when taken by the grippers 3^a is held and carried thereby through the successive printing couples and to the point of delivery, and the sheet is at no time transferred from one set of grippers to the other during or intermediate the printing operations, or at any point between the taking point T and the delivery point D; consequently absolute accuracy of registration can be obtained, and the speed of operation of the press can be greatly enhanced without impairing the quality of the product. The output of a press of this type of a given size in a given time will be more than that of an ordinary press of same size using grippers to transfer sheets from one impression cylinder to another, and to the delivery.

It is obvious that by transposing the positions of the plate and impression cylinders in either couple the press could be readily adapted to print in multi-color on one side of the sheet. It is also obvious that the number of printing couples could be increased if desired.

Having described my invention what I claim is:

1. In a printing press, the combination of two printing couples each comprising a plate and impression cylinder, the plate cylinder of one couple being gapped and the im-

- pression cylinder of the other couple being gapped; a delivery table; a guide above the delivery table; an endless carrier extending from guide to and successively between 5 the printing couples to and over the table; sheet grippers on the carrier adapted to be traversed thereby between the printing couples and to and from the delivery table, said grippers occupying gaps in the cylinders in 10 passing between the cylinders in the respective couples; a pair of feed tables, a gripper feed cylinder adapted to deliver sheets to the grippers on the carrier; and means for alternately supplying said gripper cylinder 15 with sheets from said tables.
2. In a printing press the combination of printing couples each comprising a plate and impression cylinder, one cylinder of each couple being gapped; an endless carrier 20 extending successively between the printing couples; sheet grippers mounted on the carrier and adapted to be moved thereby between the printing couples, said grippers occupying the gap in a cylinder 25 while passing between the cylinders; a feed cylinder adapted to deliver sheets to the grippers on the carrier; a pair of feed tables; a second cylinder adapted to take sheets from one table and deliver them to 30 the first feed cylinder; and a transfer cylinder adapted to take sheets from the second table and deliver them to the second feed cylinder which in turn delivers them to the first feed cylinder; whereby the sheets are 35 fed in alternation from said tables to the grippers on the carrier.
3. In a printing press the combination of two printing couples each comprising a plate and impression cylinder, the plate cylinder 40 of one couple being gapped and the impression cylinder of the other couple being gapped; a delivery table; a carrier guide above the delivery table; an endless carrier extending from the carrier guide to and successively between the printing couples 45 and back to the guide; sheet grippers mounted on the carrier and adapted to be traversed thereby between the printing couples and to and over the delivery table, said 50 grippers occupying gaps in the cylinders in passing between the cylinders in the respective couples; a feed cylinder adapted to deliver sheets to the grippers on the carrier; a pair of feed tables; a second feed cylinder 55 adapted to take sheets from one table and deliver them to the first feed cylinder; and a transfer cylinder adapted to take sheets from the second table and deliver them to the second feed cylinder, which in turn delivers them to the first feed cylinder, whereby the sheets are fed in alternation from said 60 tables to the grippers on the carrier, substantially as described.
4. In a printing press, a printing couple 65 including a plate cylinder and means co-
- acting therewith for making an impression; and means for inking said cylinder; with means for carrying sheets between the members of the printing couple to be impressed thereby, said means also passing between 70 the plate cylinder and the inking means.
5. In a printing press, a printing couple including a plate cylinder and means co-acting therewith for making an impression; and means for inking said cylinder; with 75 gripper mechanism for carrying sheets, said mechanism passing around the plate cylinder and between it and the impression member and between the plate cylinder and its inking mechanism.
6. In a printing press, a plate cylinder 80 and an impression cylinder co-acting therewith for making an impression; and means for inking said plate cylinder; with an endless carrier having means for taking sheets, 85 said means passing in its travel between the plate cylinder and inking means and between the plate cylinder and the impression cylinder.
7. In a printing press, a plate cylinder 90 and an impression cylinder co-acting therewith for making an impression; and means for inking said plate cylinder; with an endless carrier, sheet gripping devices attached to said carrier and means for causing the 95 carrier to move the sheet gripping devices between the plate cylinder and the inking mechanism and between the plate cylinder and the impression cylinder.
8. In a printing press, the combination of 100 two printing couples each comprising a plate and impression cylinder the impression cylinders being arranged close together; a delivery table at one side of the printing mechanism; gripper mechanism for holding a 105 sheet; and a traveling carrier for such gripper mechanism whereby it is caused to carry the sheet first between one impression cylinder and its plate cylinder to receive an impression on one side, then directly between 110 the impression cylinders so as to reverse the sheet, and then between the other impression cylinder and its co-acting plate cylinder to receive an impression on its other side.
9. In a printing press, the combination 115 of two printing couples each comprising a plate and impression cylinder the impression cylinders being arranged close together; and a delivery table at one side of the printing mechanism; with means for 120 gripping a sheet; and an endless carrier having a return bend portion extending above the table, said carrier carrying the gripper means and causing it to carry the sheet successively between the cylinders, and then to and over the table so as to deposit the sheet thereon from the lower run of the carrier.
10. In a printing press a plate cylinder, 125 an impression cylinder coacting therewith; 130

- an endless carrier extending around one of the cylinders and between the cylinders and having a laterally extending return loop or bend at one side of the printing mechanism; 5 a delivery table at one side of the cylinders and below the lower run of the said lateral bend of the carrier and outside the carrier; and sheet gripping means on said carrier whereby sheets may be taken first between the cylinders to be printed thereby and then carried over and delivered to the table.
- 10 11. In a printing press; the combination of two printing couples each comprising a plate and impression cylinder, the impression cylinders being arranged close together; and a delivery table at one side of the printing mechanism; with means for carrying the sheet between one impression cylinder and its plate cylinder to receive an impression on one side, then directly between the impression cylinders so as to reverse the sheet, then between the other impression cylinder and its co-acting plate cylinder to receive an impression on its other side; and then to and above the table so as to deposit sheets thereon from the lower run of the carrier; the carrier means then returning to the starting point.
- 15 12. In a printing press, the combination of two printing couples each comprising a plate and impression cylinder the impression cylinders being arranged close together; and a delivery table at one side of the printing mechanism; with an endless sheet carrying means extending from the sheet taking point between the cylinders and to and over the table and then back to the sheet taking point; and sheet holding means on said carrier adapted to take a sheet and 20 carry it between one impression cylinder and its plate cylinder to receive an impression on one side, then directly between the impression cylinders so as to reverse the sheet, then between the other impression cylinder and its co-acting plate cylinder to receive an impression on its other side, and then laterally to and above the table so as to deposit the sheets thereon from the lower run of the carrier, substantially as described.
- 25 13. In a printing press, the combination of two printing couples each comprising a plate and impression cylinder the impression cylinders being arranged close together; a delivery table at one side of the printing mechanism; gripper mechanism for holding a sheet; and a traveling carrier for such gripper mechanism whereby it is caused to carry the sheet first between one impression cylinder and its plate cylinder to receive an impression on one side, then directly between the impression cylinders so as to reverse the sheet, and then between the other impression cylinder and its co-acting plate cylinder to receive an impression on

its other side; with an offset web interposed between the table and the printing mechanism and adapted to prevent offset on the second impression cylinder; substantially as described.

70 14. In a printing press, the combination of two printing couples each comprising a plate and impression cylinder the impression cylinders being arranged close together; and a delivery table at one side of the printing mechanism; with means for gripping a sheet; and an endless carrier having a return bend portion extending above the table, said carrier carrying the gripper means and causing it to carry the sheet successively between the cylinders, and then to and over the table so as to deposit the sheet thereon from the lower run of the carrier; with an offset web interposed between the table and the printing mechanism and adapted to prevent offset on the second impression cylinder; substantially as described.

75 15. In a printing press, the combination of two printing couples each comprising a plate and impression cylinder the impression cylinders being arranged close together; with gripper mechanism for holding a sheet and means for traveling such gripper mechanism to carry the sheet first between one impression cylinder and its plate cylinder to receive an impression on one side then directly between the impression cylinders so as to reverse the sheet, and then between the other impression cylinder and its co-acting plate cylinder to receive an impression on its other side.

80 90 16. In a printing press, the combination of a pair of printing couples comprising two closely adjacent impression cylinders and means respectively co-acting with the impression cylinders to take impressions; with means for gripping a sheet and means for traveling the gripper means so as to carry the sheet to and around the first impression cylinder to receive an impression on one side, then carry the sheet directly between the impression cylinders to reverse the sheet, and then carry the sheet around the second impression cylinder so as to present the reverse side of the sheet to the printing mechanism co-acting with said impression cylinder and perfect the sheet and then deliver the sheet, substantially as described.

85 110 115 120 125 130 17. In a printing press, the combination of two printing couples each comprising a plate and impression cylinder the impression cylinders being arranged close together and substantially intermediate the plate cylinders; means for gripping a sheet and an endless carrier on which said gripping means is mounted whereby the gripping means is caused to pass first around one plate cylinder, then between one impression cylinder and its co-acting plate cylinder, then directly between the impression cylin-

ders so as to reverse the sheet, and then between the impression cylinder and the first plate cylinder, substantially as described.

18. In a printing press the combination of printing couples each comprising a plate and impression cylinder, one of the cylinders of each couple being gapped; an endless carrier extending successively between the printing couples; sheet grippers on the carrier adapted to be moved thereby between the printing couples, said grippers occupying the gap in a cylinder while passing between the cylinders in a couple; a pair of feed tables; a gripper feed cylinder adapted to deliver sheets to the grippers on the carrier; and means for alternately supplying said gripper feed cylinder with sheets from said tables.

19. In a printing press; the combination of printing couples each comprising a plate and impression cylinder, the plate cylinder of one couple being gapped and the impression cylinder of the other couple being gapped; a delivery table; a guide above the delivery table and outside the run of the carrier; an endless carrier extending successively between the printing couples to and over the delivery table; sheet grippers mounted on the carrier and adapted to be moved thereby between the printing couples and to and over the delivery table, said grippers occupying gaps in the cylinders in passing between the cylinders in the respective

couples; a pair of feed tables; a gripper feed cylinder adapted to deliver sheets to the grippers on the carrier; and means for alternately supplying sheets from said tables to the grippers on the carrier.

20. In a printing press the combination of two printing couples each comprising a plate and impression cylinder, the plate cylinder of one couple being gapped and the impression cylinder of the other couple being gapped; a delivery table at one side of the printing mechanism; a guide above the delivery table; an endless carrier extending from the said guide above the delivery table forward to and successively between the printing couples and then back above the delivery table to the guide; sheet grippers mounted on the carrier and adapted to be moved successively between the printing couples and above the delivery table, said grippers occupying the gaps in the cylinders while passing between the cylinders in the respective couples; and means for feeding sheets to said grippers on the carrier before they pass between the first printing couple; said grippers taking the sheets through the printing couple and dropping the sheets from the lower run of the carrier at the point of deposit onto the delivery table; substantially as described.

In testimony that I claim the foregoing as my own, I affix my signature.

BURT F. UPHAM.
